UNITED STATES PATENT OFFICE.

HOWARD F. CHAPPELL, OF NEW YORK, N. Y.

DRYING FINELY-DIVIDED MATERIALS.

1,375,080.

Specification of Letters Patent. Patented Apr. 19, 1921.

Application filed November 14, 1918. Serial No. 262,450.

To all whom it may concern:

Be it known that I, HOWARD F. CHAPPELL, a citizen of the United States, residing at New York, in the county of New York, State of New York, have invented certain new and useful Improvements in Drying Finely-Divided Materials; and I do hereby declare the following to be a full, clear, and exact description of the invention, such as will enable others skilled in the art to which it appertains to make and use the same.

This invention relates to the drying of finely-divided materials, such as fine graphite, fine concentrates, and more particularly the fine material discharged as filter cake from vacuum and pressure filters, and the like. One of the principal uses of the invention consists, for instance, in the drying of the filter cake discharged from a filter press of the well-known Kelly type in the treatment of finely-divided leached calcined alunite.

Materials of this general character, and especially leached calcined alunite (alumina) filter cake, are frequently so fine that after they have parted with a considerable part of their moisture a relatively slight draft of air will carry away a notable amount of the material. Accordingly, serious losses accompany the drying of such materials in the usual types of so-called direct-heating apparatus relying upon a circulation of heated air, products of combustion, or the like, over and in contact with the charge; and, even where means are employed, such as a cyclone dust collector, for recovering, as far as it is feasible to do so, the material carried away from the charge, such recovery is accompanied in large part with re-condensation of the moisture, so that the recovered material must be returned to the drier. The employment of stirring devices in these direct driers magnifies their dust-producing characteristics to such a degree as to render them wholly impracticable for economical service for the treatment of these extremely finely-divided materials.

On the other hand, when the drying heat is applied to materials of this general character indirectly (for instance, by heating the bottom of a stationary pan or other receptacle containing them) their low-conductivity for heat makes it difficult and expensive to continue the drying operation to ad-

vantage as soon as a bottom layer of comparatively moderate depth of dry material has formed.

The present invention has for its object not only to provide an efficient drier for these finely-divided materials, avoiding the dust losses referred to, but also to speed up the drying operation by utilizing to special advantage the products of combustion or other heating medium, and to make the operation continuous and readily regulable by the operator, who can at all times observe its progress and can regulate its conditions to suit the requirements of the charge, the desired or predetermined output per unit of time, and the degree of dehydration contemplated.

To this end, the invention provides an apparatus wherein the charge may be fed continuously, at a rate to be determined by the operator, and may be spread out at a regulable depth upon a heated endless traveling platform. The platform, as will hereinafter more fully appear, consists of a series of plates or pans, assembled to form the links of an endless sprocket chain, and its weight is borne by traction wheels traveling upon suitable rails. Sprocket wheels, one of which is adjustable to serve as a means for tightening the endless platform, serve to actuate it at the desired speed.

The upper strand of the traveling platform forms the roof of a heating flue, through which pass the heating gases. These gases enter at one end of the flue and take their exit at the other, and the draft is so regulated that there will exist in this flue a minus pressure and consequently a tendency to draw into the flue the water vapors given off from the heated charge above, through such passages or apertures as are available for that purpose. Such passages and apertures, for instance, exist between the outer edges of the platform and the side walls of the drier structure and between the bottom of the platform and the upper edges of the side walls of the draft flue.

The drier structure is provided, above the traveling platform, with a cover plate, and, consequently, as the charge gives off its water vapor in the drying operation, the tension of the vapors aided by the draft in the flue below withdraws them continuously and discharges them with the spent heating gases into the drier flue stack. The opening from the flue into the stack should be in

the lower part of the flue so as to assist in overcoming any possible tendency for the combustion gases to work into the compartment above the charge. So also, at intervals, above the charge, there are preferably located transverse baffles extending from one side wall of the compartment to the other, these baffles having as their function the prevention of the watery vapor given off at one zone of the charge from passing on to another zone and being re-absorbed thereby instead of being taken down directly into the draft flue.

Where filter cake from leached calcined alunite is to be dried, I prefer to load it upon the traveling platform at the hotter end of the flue, *i. e.*, at the end where the hot gases enter the flue, and to so actuate the platform that the charge will move in the same direction as the hot gases. As a consequence, the high temperature of the gases acting upon the fresh moist alumina will almost immediately bring the moisture to a point where it will be expelled in large volume, by reason of its vapor tension, from the material and this initial volume of moisture will promptly take its exit into the flue below. A crust tends to form very quickly over the material on the platform. This is broken up by means of scrapers in the shape of plow shares which project down into the charge to a distance which just clears the platform. These scrapers are so shaped and so arranged as to turn the material over slowly without causing dust, rolling it over in manner similar to the action of a plow in turning over the sod of a grass field. The moisture from the material, as hereinbefore indicated, passes down into the combustion flue, by reason of the vapor tension of the moisture aided by the draft of the flue.

In the accompanying drawings, there is illustrated a form of apparatus embodying the characteristic features of the invention, and showing its preferred practice, although it will be understood that the particular details of construction may be varied in practice, within wide limits, according to the particular material to be treated and the specific conditions of use.

In the drawings,—

Figure 1 represents (partly broken away) a vertical longitudinal section of the furnace structure;

Fig. 2 represents a horizontal longitudinal section;

Fig. 3 represents a transverse vertical section, taken on a plane indicated by the line 3—3 of Fig. 1;

Fig. 4 represents a like view on the line 4—4 of Fig. 1.

Similar letters of reference indicate similar parts in both views.

Referring to the drawing, B indicates a

heating flue communicating at one end with an inlet passage D for the admission of the heating medium, which may consist of products of combustion from any suitable heating furnace. The flue B discharges at its opposite end by means of a passage E communicating with the furnace stack, as shown. On opposite sides of the flue B are the ledges *a* of the furnace structure, which support the longitudinally extending angle irons *b*, serving as foundation plates for the rails *c* which support the carrying wheels *d* of the movable platform.

The movable platform consists of a series of plates *f*, which are linked together to form an endless-chain structure, which is distended by the sprocket wheels *Y*, one of which is adapted to be operated from any suitable source of power, and one of which is capable of adjustment longitudinally of the furnace structure, so as to keep the movable platform taut. In addition to the rails *c* the apparatus is provided with rails *g* arranged below the flue and which serve to support the lower strand of the plates making up the movable platform on their return movement through the apparatus. By reference to Fig. 3, it will be noted that between the upper edge of the angle irons *b* and the bottom surface of the plates *f* of the movable platform there is a clearance space which is provided to permit the water vapors given off from the material to be drawn down into the flue B below.

The vertical walls of the structure in which the flue B is located are surmounted by a cover-plate *L*, and, below this cover plate are arranged a series of scrapers in the form of plow shares *i*, so shaped and arranged as to dip into the charge and to turn over slowly and without material production of dust the charge of leached calcined alunite, or like material, to be dried, and also to break up any crusts that may tend to form within or upon said material.

A suitable hopper *Z* supplies the moist material to be dried to the upper surface of the movable platform, and the depth of the layer upon the platform is determined by the adjustable gate *z* operated by the handle *t*, or the like.

At the exit end of the movable platform is arranged the receiving pit *J* provided with the slide *j* which serves to seal the apparatus at that point by means of the dried material discharged upon the movable platform. At intervals along the cover *L* of the drier are arranged partitions extending transversely of the entire width of the space in which they are located and consisting of a vertically adjustable depending plate *l*,—the function of these partitions being to localize the moisture given off at different parts in the longitudinal travel of the material being dried, so as to prevent the mois-

ture given off at an advanced zone of the drier from passing rearwardly to the zones where the drying operation has progressed to a greater degree, and to insure that the moisture given off at any particular zone shall pass down into the combustion draft flue at substantially the point where the moisture is generated.

Although the invention is not limited to locating the feed hopper at the hotter end of the combustion draft flue, I nevertheless prefer to locate it at that point, in most instances, so that the greater part of the moisture shall be given off from the material, per unit of travel, at the region where it is first discharged upon the traveling platform; although, as will be understood, the requirements of the heating of such materials will make it preferable to locate the feed hopper at the colder end of the heating flue and to gradually raise its temperature by carrying it progressively toward the hotter end thereof, the direction of travel of the movable platform being determined accordingly.

From the foregoing description, the mode of operation of the invention will now be clearly apparent. The leached calcined alunite, or other finely-divided material to be dried is fed upon the upper surface of the movable endless-chain platform, at a depth of layer determined by the adjustment of the gate z . As the platform advances, the material encounters successively the series of plows or scrapers i which turn the material over so as to expose new surfaces to the action of the heat transmitted through the plates and to prevent whatever tendency may exist in the material to become caked or incrusted at any point throughout the charge. The moisture given off from the material, passes down into the flue B , by reason of the vapor tension of the moisture, assisted by the draft existing in the flue, and is continuously carried off through the exist passage E to the stack or other point of discharge. The speed of the movable platform, and the temperature of the products of combustion or other heating medium employed in the draft flue B are regulated to correspond to the drying effect desired. The resulting effect is that the finely-divided moist material is discharged from the end of the upper strand of plates of the movable platform dried to the degree required, and without dust loss. The action of the plows or scrapers insures uniformity of the drying operation and the prevention of any substantial adhesions to the plates of the movable platform, and, inasmuch as the moisture passes off mainly by reason of its vapor tension, it carries practically no dust with it, so that the finely-divided material, in the dried condition required is obtained as the product of the op-

eration in practically its entirety. So also, because of the dustless character of the operation, the drying may be carried on without discharging into the atmosphere any material amount of the finely-divided material, so that, not only from the standpoint of recoverable output, but also from the standpoint of sanitation and preservation of the surrounding locality from dust deposits the operation is correspondingly advantageous. This advantage is incident to the fact that in the drying operation, no air passes over the material, the moisture passing off by reason of its vapor tension aided by the slight draft in the flue, and this result being further accompanied with a large output, because of the speed and thoroughness with which the moisture is removed, and the capacity of the apparatus to treat continuously large quantities of the material to be dried.

As shown in Fig. 4, the apparatus is preferably provided with longitudinal guard plates w having depending edge flanges x . These guard plates extend from end to end in the upper compartment of the drier and have for their function to prevent any material infiltration of the combustion gases into the space above the material being dried; at the same time, they fit the space in which they are located rather loosely so that they do not prevent the downward passage of the moisture into the combustion flue, under the influence of their own tension and the draft of the flue.

Having thus described my invention, what I claim is:

1. A drier for finely-divided material, comprising an upper and a lower compartment, separated by a movable platform, the lower compartment constituting a flue for the passage of heating gases, an inlet below said platform for admitting the heating gases to the flue and an outlet also below said platform for discharging the gases from the flue, and means for supplying the material to be dried to the upper side of the platform; substantially as described.

2. A drier for finely-divided material, comprising an upper and a lower compartment, separated by a movable platform, the lower compartment constituting a flue for the passage of heating gases, and communicating with the upper compartment by suitable passages for the moisture given off in the drying operation, and means for supplying the material to be dried to the upper side of the platform; substantially as described.

3. A drier for finely-divided material, comprising an upper and a lower compartment, separated by a movable platform, the lower compartment constituting a flue for the passage of heating gases, and communicating with the upper compartment by suit-

able passages for the moisture given off in the drying operation, the upper compartment being provided at intervals along its length with transverse baffles correspondingly localizing the moisture given off from the traveling charge on the platform so that it will pass down into the flue at different longitudinal zones, and means for supplying the material to be dried to the upper side of the platform; substantially as described.

4. A drier for finely-divided material, comprising an upper and a lower compartment, separated by a movable platform, the lower compartment constituting a flue for the passage of heating gases, and the upper compartment being provided with plows or scrapers for turning over the material during the drying operation and preventing it from being incrusted upon the platform, an inlet below said platform for admitting the heating gases to the flue and an outlet also below said platform for discharging the gases from the flue, and means for supplying the material to be dried to the upper side of the platform; substantially as described.

5. A drier for finely-divided material, comprising an upper and a lower compartment, separated by a movable platform, the lower compartment constituting a flue for the passage of heating gases, said movable platform being made up of a series of elements linked together to form an endless chain, sprocket wheels for actuating the endless chain platform, and traction wheels therefor adapted to run upon rails located within the drier structure, and means for supplying the material to be dried to the upper side of the platform; substantially as described.

6. A drier for finely-divided material, comprising an upper and a lower compartment, separated by a movable platform, the lower compartment constituting a flue for the passage of heating gases, said movable platform constituting an endless chain structure, sprocket wheels for actuating the platform, traction wheels for supporting its weight, and rails upon which the traction wheels run, the rails for supporting the upper strand of the elements of the endless chain platform being located on opposite sides of the flue compartment; substantially as described.

7. A drier for finely-divided material, comprising an upper and a lower compartment, separated by a movable platform, the

lower compartment constituting a flue for the passage of heating gases, said movable platform constituting an endless chain structure, sprocket wheels for actuating the platform, traction wheels for supporting its weight, and rails upon which the traction wheels run, the rails for supporting the upper strand of the elements of the endless chain platform being located on opposite sides of the flue compartment, and the rails for supporting the lower strand of the elements of the movable platform being located in a space below the flue compartment; substantially as described.

8. A heater for finely-divided material, comprising an upper and a lower compartment supported by a movable platform, the lower compartment constituting a flue for the passage of heating gases, the said movable platform consisting of an endless chain structure provided with traction wheels and actuated by sprocket wheels, means for feeding the finely-divided material in an even layer to the upper side of the platform, plows or scrapers for turning over the material during its progress through the drier, means for localizing the moisture given off from the material to different zones along the length of the upper compartment, and passages connecting these zones with the flue compartment so as to permit the moisture by reason of its expansion, aided by the draft in the flue compartment, to pass down into the flue compartment; substantially as described.

9. In a drier for finely-divided material, comprising an upper and a lower compartment, separated by a movable platform, upon which the material to be dried is supplied, means for sealing the drier at the discharge end of the movable platform, said means consisting of a receiving pit into which the dried material passes from the platform, and a partition extending into said pit; substantially as described.

10. A drier for finely-divided material, comprising an upper and a lower compartment, separated by a movable platform, the lower compartment constituting a flue for the passage of heating gases, means for supplying the material to be dried in the upper side of the platform, and plates for preventing material infiltration of the combustion gases into the space above the drying material; substantially as described.

In testimony whereof I affix my signature.

HOWARD F. CHAPPELL.
